UNITED STATES PATENT OFFICE.

PAUL VICTOR PARSY, OF PARIS, FRANCE.

CRUCIBLE-FURNACE FOR MELTING METALS.

1,308,190.

Specification of Letters Patent.

Patented July 1, 1919.

Application filed December 26, 1916. Serial No. 138,987.

To all whom it may concern:

Be it known that I, PAUL VICTOR PARSY, of 5 Rue Jules Lefebvre, Paris, in the Republic of France, civil engineer, have invented Crucible-Furnaces for Melting Metals, of which the following is a full, clear, and exact description.

In most furnaces at present in use for melting copper, brass, or other metals, the crucible is embedded in a mass itself of burning coke.

This method of heating the crucible necessitates on the part of the melter a special professional skill in attending to the fire.

On the other hand, the burning coke deteriorates rapidly the crucibles by the contact of these latter with the slag.

The present invention relates to a crucible furnace for melting metals constructed in such a manner as to obviate the inconveniences above mentioned.

The present kind of furnace is characterized essentially by the fact that it is heated by gas, with regeneration of the heat to heat the air supply, and that it comprises a combustion chamber and a smaller chamber arranged in such a manner that the flames may pass easily from the combustion chamber into the smaller chamber without being hindered by the residues of fused material or dross, which may be removed without impeding the working of the furnace.

By way of example, the invention is represented in the accompanying drawing which shows a vertical section of the present system of furnace.

As seen in the drawing, the furnace comprises a small upper or melting chamber *a* in which is placed the crucible *b*. This small chamber *a* is closed at its upper part by a cover *c*, and communicates, at its lower part, with a combustion chamber *d* placed at a lower level. This chamber has an inclined surface *e* and it is closed by a door *f* arranged upon the outer face of the furnace.

In the lateral walls of the chamber *d* are arranged burners *g* communicating on one hand by the conduits *h* with a passage *h'* leading the gas from a gas producer, and on the other hand by means of a conduit *i* with a heat retaining chamber *i'* which is shown diagrammatically in the drawing and may be provided with flues or the like for

leading the incoming air alongside of the outflowing gases in any suitable or well known manner.

The burners *g*, which lead into the chamber *d*, the gas coming from the passage *h'* and the heated air coming from the heat retaining chamber *i'*, are placed at the upper part of the said chamber so that the flames may rise into the small chamber *a* containing the crucible without being hindered by the matter which flows from this latter in the contrary direction upon the inclined surface *e*, and which consists of the waste metal or dross.

In consequence of the high temperature of the combustion chamber *d*, this matter is maintained in a melted state and it accumulates in the bottom of the said chamber from which it may be withdrawn through the door *f*.

The combustion gases, after having enveloped the crucible, are directed by the conduits *j* and *j'* to the heat retaining chamber *i'* to heat the secondary air.

However, during the time necessary for pouring, when the cover *c* is removed, a free communication may be established with the chimney *k* by operating in any convenient manner the bell or valve *l*. This operation of the bell *l* enables a strong suction of the gases to be effected which facilitates the raising of the crucible.

The system of furnace which has just been described may be modified according to its applications while retaining the general arrangements to assure its practical operation.

I claim:—

1. In a crucible melting furnace the combination with a crucible and a melting chamber surrounding said crucible, of a combustion chamber located at a lower level than and connected by a sloping passage with the bottom of said melting chamber, gas and air conduits opening into the upper part of said combustion chamber, and a door for permitting the removal of molten matter from said combustion chamber.

2. In a crucible melting furnace the combination with a crucible and a melting chamber surrounding said crucible, of a combustion chamber located at a lower level than and connected with said melting chamber, said combustion chamber having an in-

clined wall extending from the bottom thereof to the bottom of said melting chamber, gas and air conduits opening into the upper part of said combustion chamber, a door for permitting the removal of molten matter from said combustion chamber, a flue for leading the burnt gases away from said melting chamber, and means for utilizing the heat carried away by the burnt gases to preheat the air on its way to the combustion chamber. The foregoing specification of my crucible furnace for melting metals, signed by me this fourth of December, 1916.

PAUL VICTOR PARSY.
